UNITED STATES PATENT OFFICE.

ROBERT S. CADE, OF CANTON, OHIO.

COMBINATION METAL WEATHER-STRIP AND GUIDE FOR WINDOW-SASHES.

1,348,205.

Specification of Letters Patent.

Patented Aug. 3, 1920.

Application filed January 3, 1919. Serial No. 269,413.

To all whom it may concern:

Be it known that I, ROBERT S. CADE, a citizen of the United States, residing at Canton, in the county of Stark and State of Ohio, have invented new and useful Improvements in Combination Metal Weather-Strips and Guides for Window-Sashes, of which the following is a specification.

This invention relates to combination 10 weather strips and guides for window sashes.

One object of the invention is to provide sliding connections between the sashes and sides of the window frame, including spring 15 metallic strips acting as sliding guide members and also as sealing devices to exclude the entrance of air, dust, etc.

A further object of the invention is to provide metallic guiding and sealing strips 20 which exert spring pressure on the guide of the frame, whereby rattling of the sashes will be prevented, and which strips may be adjusted to vary their spring pressure.

A still further object of the invention is 25 to provide a guide construction which simplifies the general construction of the window frame, and permits of the use of either wood or metal stop strips, as desired.

A still further object of the invention is 30 to provide strips for efficiently closing the joints between the meeting rails of the sashes and between the sashes and the lintel and sill of the window frame.

A still further object of the invention is 35 to provide a structure of the character stated which greatly simplifies the manufacture of window frames and the sashes therefor, and by the use of which the usual guide strips and beads commonly employed in 40 such frames are eliminated.

With these objects in view, together with others which will appear as the description proceeds, the invention resides in the novel construction, combination and arrangement 45 of parts, all as will be described more fully hereinafter, illustrated in the drawings, and particularly pointed out in the claims.

In the drawings:

Figure 1 is a view in elevation of a window frame and sashes embodying my invention,

Fig. 2 is an enlarged horizontal section through one side of the window frame and both sashes,

Fig. 3 is a vertical section through the frame and sashes, and

Fig. 4 is a perspective view showing in detail the construction of one of the spring metal strips.

The invention, generally stated, resides in 60 providing the inner faces of the side members of the window frame with spaced longitudinally disposed parallel grooves or channels arranged in pairs, the grooves or channels of each pair being spaced apart a 65 distance substantially equal to or slightly greater than the width of the stiles of the sashes, and resilient metallic plates or strips are secured to the stiles and engage in the 70 said grooves and frictionally bind with the walls thereof. While the frictional engagement of these strips is sufficient to exclude the passage of air, dust, etc. through the channels, it is not sufficient to interfere with the free sliding movement of the sashes. 75 These strips, also, possess sufficient strength and rigidity to maintain the sashes in proper position within the frame, so that the said sashes are firmly held against displacement. 80 The invention further comprehends the use of similar means at the top of the window frame, at the bottom thereof, and at the meeting rails of the sashes to prevent the passage of air through the window frame 85 when the sashes have been moved to closed 85 position.

In the drawings, 5 indicates the sides of the window frame, 6 the lintel thereof and 7 the sill. In the present instance the invention is illustrated as applied to a window 90 frame formed of cement or concrete, and the sides 5 and lintel 6 are of wood and are firmly secured to the sides and top of the frame. This particular construction and method of forming the frame need not be 95 adhered to in carrying out the invention, as the ordinary wooden frame may equally as well be used.

The inner faces of the sides 5 of the frame are provided with spaced channels or grooves 100 8, the same being parallel to each other and coextensive with the said sides. The grooves are arranged in pairs, a pair of each of said grooves being provided for each sash. The lintel 6 of the frame is provided with a 105 pair of spaced parallel grooves extending from one end to the other thereof, and these grooves communicate at their ends with the grooves or channels in the sides 5 of the frame with which the upper sash is used. 110

The lower sash is indicated at 9, while 10 represents the upper sash. These sashes

may be of the usual well known construction, and the stiles thereof upon both their inner and outer faces are provided with metallic strips or plates 11. These plates are of equal length with the stiles, and are secured to the latter near their inner edges by screws or other securing elements indicated generally at 12. It is preferred that the inner extremities of these plates be bent upon themselves as shown so as to render the joint between the stiles and the window frame substantially air tight. This particular construction, in addition to forming an air seal, strengthens the structure and relieves to a great extent the strain upon the retaining screws 12.

The outer edges of the strips or plates extend into the grooves 8, and the portions of these strips which are inclosed by the grooves are bent backwardly upon themselves and are rounded as at 13 to enable the said plates to frictionally engage with both side walls of the channels or grooves. By reason of this double engagement of the strips with the walls defining the grooves, a double air seal is provided, and by doubling the plates upon themselves the same are strengthened or reinforced. As the portions of the strips extending into the grooves are round, there will be a comparatively small amount of contacting surface between the strips and the channel walls, and while this area of contact is sufficient to exclude the passage of air through the channels, it is not sufficient to create such friction as to retard or impair the free movement of the sashes. The degree of pressure of the bent portions of the strips upon the channel walls may be increased by expanding the bent portions of the strips by the insertion of a pointed or flat instrument therein.

The meeting rails of the sashes 9 and 10 are cut so as to snugly interfit when the sashes have been moved to closed position, and a metallic strip 14 is secured to the upper surface of the sash 9 so as to extend over the joint between the rails when the sashes are closed. This strip is applied to the rails by driving screws or tacks through one edge thereof, and the free end of the strip is bent upon itself as at 13 similarly to the bent portions of the strips upon the stiles.

The sill 7 is provided upon its upper face with a channel to receive the bottom rail of the lower sash, and one edge of the channel is provided with a beveled or inclined wall to be engaged by a similar inclined surface at the lower edge of the said bottom rail. To exclude air, dust, etc., gaining access to the room below this bottom rail, a resilient metallic air excluding strip 15 is employed. This strip, in the present instance, is fastened to the inclined surface of

the lower sash rail, and is secured thereto by screws or tacks as shown. This strip has a bent portion 13 similar to the strips at the sides and top of the sash, and it will be understood that the weight of the sash when the latter is lowered will cause this resiliency bent portion to tightly seal the joint between the sill and the sash.

In order that air will be prevented passing into the room above the upper sash when the latter is at the limit of its upward movement, strips 16 are used. These strips are similar in construction to those upon the stiles of the sashes, and are arranged one upon each face of the top rail of the upper sash 10. The free edges of these plates or strips enter the grooves 17 in the lintel 6 when the sash is in raised or closed position.

While the friction between the various metallic plates and the walls of the grooves which they enter need only be sufficient to exclude the passage of air, dust, etc., around the edges of the sashes, still this friction may be increased to such extent as to maintain the sashes in their various positions of adjustment, thus eliminating the use of window weights and other devices commonly employed for this purpose.

From the foregoing it is obvious that I have provided a window construction such as will enable the sashes to slide smoothly and evenly without the use of the beading and ribs heretofore used for the confinement and guidance of these sashes. At the same time, air will be prevented passing around the edges of the sashes when the latter have been moved to closed position, as a double air seal is provided at each edge of the stiles, upon the upper rail of the top sash, at the meeting rails of the upper and lower sashes and at the juncture of the bottom rail of the lower sash with the sill. The strips or plates are of simple and inexpensive construction and may be easily and quickly applied to and removed from the sashes without the use of special skill or tools.

While the above is a description of the preferred embodiment of the invention, it is obvious that the invention is not necessarily restricted thereto, as various changes in the minor details of construction of the strips and sashes may be made without departing from the invention as defined by the claims.

I claim:—

1. The combination with a window frame including a pair of sliding sash sections, of relative narrow grooves being formed in the opposed faces of the vertical members of the frame, one of said grooves being disposed at opposite sides of each of said sash sections and having their inner walls in alignment with the corresponding faces of the latter, and flat metallic strips secured on opposite sides of each of said sash sections and projecting into said grooves in con-

tacting relation with the inner walls thereof, said metallic strips having their edge portions within the grooves formed to provide folded portions disposed in contacting relation with the outer walls of the latter.

2. The combination with a window frame, including an upper sliding sash section and a lower sliding sash section, of relative narrow grooves being formed in the opposed faces of the vertical members of the frame and coextensive therewith, one of said grooves being disposed at opposite sides of each of said sash sections and having their inner walls disposed in alinement with the corresponding faces of the latter, and flat metallic strips secured on opposite sides of

said sashes and projecting into said grooves in contacting relation with the inner walls thereof, said metallic strips having their opposite edges reversely folded to provide 20 inturned portions, one of said inturned portions of each of said strips being arranged to contact the face of said sash sections and the other of said inturned portions to engage the outer walls of each of said grooves 25 whereby the intermediate portion of said strips is retained firmly in contact with the alining surface of said sashes and the inner walls of said grooves.

In testimony whereof I affix my signature. 30

ROBERT S. CADE.
